Joseph H. Bartlett of New York,
Letter Patent 1,219,115 Date 10/10/1917

Design for the Frame of Sewing and Embroidering Machine

The schedule is joined to this Letter Patent and making part of the same,
as also, as
to all whom it may concern:

6. Do it is known that I, Joseph H. Bartlett, of the
City, County, and State of New York, have invented and designed a
new and useful design for the Frame of Sewing, Embroidery, and
other Machines of like nature of which the following is a full, exact
and clear description thereof, reference being had to the accompanying
drawings, part of the specification.

This drawing is in the annexed representation of
elevation and plan (full size). The frame consists of a
representative of a rectangular frame. B. B, the bed made from
sides or spars, &c, bearing for the shaft, D. D, a conical shaped arm
to support the post rod, E, a shield for containing the trademarks
name, F, bearing for holding the sliding base, for needle and presser
fork, the parts shown in dotted lines, G and H, are only required when
the post and the base are used & is the support for the post rod, H, a
bearing against which it commutes.

I claim the design for the Frame of Sewing, Embroidering,
and other machines of like nature, substantially as shown and de-
scribed.

Witnesses,

J. H. Bartlett
A. J. Quinn
